WINDOW LOCK

Charles M. Flynn, Jr., Wyandotte, Mich., assignor to
C. M. Flynn Mfg. Co., Inkster, Mich., a partnership

Application October 15, 1958, Serial No. 52,992

Term of patent 14 years

(Cl. D50—7)

Fig. 1 is a perspective view of a window lock, showing my new design.

Fig. 2 is a front elevational view thereof.

Fig. 3 is a top plan view thereof.

Fig. 4 is a left end elevational view thereof.

Fig. 5 is a right end elevational view thereof.

Fig. 6 is a bottom plan view thereof.

Fig. 7 is a rear elevational view thereof.

I claim:
The ornamental design for a window lock, as shown.
